UNITED STATES PATENT OFFICE.

JOSEPH EDGAR STANGER, OF BRIDGETON, NEW JERSEY.

LIFE-SAVING DEVICE FOR AIRCRAFT.

1,290,798.

Specification of Letters Patent.

Patented Jan. 7, 1919.

Application filed July 11, 1918. Serial No. 244,492.

To all whom it may concern:

Be it known that I, JOSEPH E. STANGER, a citizen of the United States, and a resident of Bridgeton, in the county of Cumberland and State of New Jersey, have invented certain new and useful Improvements in Life-Saving Devices for Aircraft, of which the following is a specification.

My invention relates to improvements in life saving devices, it being more particularly adapted for use in connection with aircraft of all kinds, and it consists in the constructions and arrangements herein described and claimed.

An object of my invention is to provide a life saving device to be used more especially by aviators, which is light, small in bulk and consequently easily carried when strapped in place and causing no inconvenience to the wearer in his movements.

A further object of the invention is to provide a parachute rolled in a small bundle and carried in a pocket on the back of a belt strapped around the body of the wearer beneath the arms.

A further object of the invention consists in the peculiar manner of folding the parachute prior to rolling it, consisting of turning up the edge all the way around so that this edge is initially turned out to catch the air and insure the opening of the parachute.

Other objects and advantages will appear in the following specification, reference being had to the accompanying drawings in which:

Figure 1 is a perspective view showing the life saving device strapped in place on the back of the aviator,

Fig. 2 is a front view illustrating the appearance of the front of the belt,

Fig. 3 is a perspective view of the device showing the parts separated.

Fig. 4 is a perspective view showing the life saving device in use,

Fig. 5 is a perspective view illustrating the action on initially opening the parachute, and

Figs. 6 and 7 are detail sectional views illustrating the principle of the up-turned edge of the parachute.

Fig. 8 shows a modification of the belt portion of the device.

In applying the life saving device, the belt 1 is placed around the body under the arms as illustrated in Fig. 2, with the straps

2 applied to the shoulders. The straps 2 are fastened to the belt 1 at the front and back as illustrated in Fig. 3. The ends of the belt 1 are provided with a plurality of eyelets 3 in which the cord 4 is laced in any desired manner and tied in a knot at 5.

The belt 1 instead of consisting simply of the plain flexible body illustrated in Fig. 3, may be modified in order that the wearer may float should he fall into the water by adding an air compartment 16 around the belt. This compartment is simply in the nature of a pocket made of any suitable material which is provided with a valve 17. Since the belt is strapped to the body high up under the arms, it becomes an easy matter for the wearer to reach down and inflate the compartment 16. Fig. 8 shows the arrangement above described and also shows how the ends of the belt may be fastened together by buckles and straps 18. It should be understood that a number of different fastening means may be employed to secure the belt. When the compartment or pneumatic chamber 16 is inflated the belt becomes a life preserver in water.

The particular arrangement of lacing the belt together will be governed largely by the taste of the wearer and also by the size of his body. The three sets of eyelets may be placed together as shown in Fig. 2 so that the cord 4 may be laced through all of them under the condition that the wearer's body is small enough to necessitate this. Obviously if the body is larger, the belt will be lengthened accordingly so that the two first sets only of eyelets beginning from the ends of the belt are used.

A pocket 6 sewn or fastened to the back of the belt 1 in any suitable manner, holds the parachute 7 when rolled into a bundle as shown in Figs. 1 and 3. The parachute is made of any suitable material and may be of any desired size. A plurality of cords 8 secured in eyelets 9 at equal distances along the edge 10 of the parachute are assembled in a joint 11. The joint 11 is fastened to a ring 12 to which one end of a release rope 13 is fastened.

The other end of the release rope 13 is fastened to a loop or strap 14 slipped over one end of the belt 1. The rope 13 lies across the shoulder of the wearer somewhat as illustrated, and when it is desired to release the parachute by pulling it out of the

pocket 6, the wearer grasps the rope 13 as shown in Fig. 1 and jumps at the same time.

In folding and rolling the parachute 7, the edge 10 is turned up approximately 5 eight inches all the way around along the line 15. This edge is turned up prior to rolling the parachute into a bundle. Figs. 5 and 7 illustrate the purpose for turning up the edge. When the parachute unfolds initially and the cords 8 commence to become taut, the edge 10 will be the first to be pulled over so that a gutter *a* as illustrated in Fig. 7, is formed all the way around. This gutter is inverted as shown and catches the air 10 as indicated by the arrows. The tendency of the outer edge 10 being to pull down, the air is directed toward the inside of the parachute so that it rapidly fills and the folds are forced to expand.

15 This feature is very important in that the safety of the device depends thereon to a great extent. This folded up edge insures the rapid expansion of the parachute so that the wearer drops a considerably shorter distance before his fall is retarded, than is the case in parachutes where this provision is omitted.

20 The operation will at once be apparent from the drawings but by way of review 30 it may be briefly stated that all that is required of the wearer in case of an emergency, is simply to grasp the release rope 13 and simultaneously pull thereon as he makes the leap. The first action that occurs after 35 the descent commences, is the formation of the inverted gutter *a* which directs the air to the inside of the parachute and forces the folds apart. The parachute is thus rapidly 40 opened to the fullest extent as shown in Fig. 4 and the momentum of the body is checked.

45 It may be stated in closing that the materials of which the various parts are made will be a matter of selection in the making 50 of the device. The devices will also be made in different sizes so that bodies of different girths can readily be fitted.

55 While the construction and arrangement of the device as herein described and claimed 50 is that of a generally preferred form, obviously slight modifications in the construction and arrangement of the device may be made within the scope of the claims without departing from the spirit of the invention.

55 I claim:-

1. A life saving device comprising a belt 60 secured around the body, a parachute attached to the belt, and means embodied in the parachute for insuring the spreading of the parachute, said means comprising a turned-up edge arranged to form into an

inverted gutter and act as an air deflector to the inside.

2. A life saving device comprising a belt 65 secured around the body, means for supporting a rolled-up parachute on the back of the belt, a parachute normally rolled up and supported on the belt by said means, connecting means between the parachute and said belt, and a turned-up flap around the 70 edge of the parachute having means for receiving said connecting means, said flap opening into an inverted gutter to act as an air deflector toward the inside and insuring the rapid spreading of the parachute, 75 on the initial portion of the descent.

3. A life saving device comprising a belt 80 secured around the body, lacing eyelets in the ends of the belt, a lacing cord for fastening the belt to the body, shoulder straps carried by the belt, a pocket on the back of the belt, a parachute normally rolled up and placed in the pocket, a turned-up flap around the edge of the parachute adapted to initially receive air to act as a deflector 85 and insure the spreading of the parachute, connecting means including cords attached to the edge of the parachute and a release rope lying across the shoulder of the wearer, and means comprising a strap on the belt 90 having the other end of the release rope secured thereto.

4. A life saving device comprising a belt 95 applicable to the body, means for fastening and supporting the belt, a parachute pocket attached to the back of the belt, inflatable compartments adjacent to said pocket to occupy places beneath the arms of the wearer, and a parachute normally rolled up 100 into a bundle and occupying the pocket, with connecting means between the parachute and the front of the belt, said means including a release rope coming in front of the wearer and arranged to be grasped when falling.

105 5. A life saving device for retarding the fall of the wearer and supporting him in the water, comprising a belt with an inflatable compartment, attachable to the body, a valve in the compartment near the mouth 110 of the wearer to be readily reached for the inflation of the compartment while falling, a parachute normally rolled up and held in place on the belt to avoid encumbering the wearer, and means connecting the parachute to the belt, said means including a release cord passing over the shoulder to enable grasping thereof to release the parachute, and a loop forming the connection between the release cord and the belt.
